UNITED STATES PATENT OFFICE

127,354

DESIGN FOR A COMBINED FAN AND PLAYING CARD HOLDER

Joseph A. Paradise, Detroit, Mich.

Application March 11, 1941, Serial No. 99,501

Term of patent 7 years

To all whom it may concern:

Be it known that I, Joseph A. Paradise, a citizen of the United States, residing at the city of Detroit, in the county of Wayne and State of Michigan, have invented a new, original, and ornamental Design for a Combined Fan and Playing Card Holder, of which the following is a specification, reference being had to the accompanying drawing, forming part thereof.

Fig. 1 is a plan view of a combined fan and playing card holder showing my new design.

Fig. 2 is a side elevation of my combined fan and playing card holder.

I claim:

The ornamental design for a combined fan and playing card holder, as shown.

JOSEPH A. PARADISE.
